(57) **CLAIM**

The ornamental design for a hatch for a vehicle, as shown and described.

DESCRIPTION

FIG. 1 is a rear perspective view of a hatch for vehicle according to an exemplary embodiment;

FIG. 2 is a left side view thereof;

FIG. 3 is a front perspective view thereof;

FIG. 4 is a top view thereof;

FIG. 5 is a right side view thereof;

FIG. 6 is a rear view thereof; and,

FIG. 7 is a bottom view thereof.

The broken lines in the drawings illustrate portions of the hatch for a vehicle that form no part of the claimed design.
